ELECTRICAL APPARATUS

Arthur C. Ten Cate, Downers Grove, Ill., assignor
to Oak Mfg. Co., Chicago, Ill., a corporation of
Illinois

Application July 8, 1948, Serial No. 37,551

9 Claims. (Cl. 274—10)

1

This invention relates to an automatic record changer construction and particularly to that portion of a changer for feeding records. The invention hereinafter disclosed provides feeding means operating against the edge of records and is adapted to move the records in their own plane. In the record changers to which this invention pertains, the records or a stack of records are generally supported on a spindle provided with a suitable offset or cam with each record being adapted to be moved in its own plane to permit the same to drop down on a turntable. Certain portions of the construction disclosed and claimed herein are disclosed in a co-pending application, S. N. 785,856 filed November 14, 1947, now Patent Number 2,558,474.

The invention will now be described in connection with the drawing wherein Fig. 1 is a top plan view of a record changer embodying the invention with the turntable partly broken away. Fig. 2 is a sectional view on broken line 2—2 of Fig. 1. Fig. 3 is a plan view of the record feeding means used in the construction disclosed in Figs. 1 and 2. Fig. 4 is an elevation of the feeding member shown in Fig. 3 removed from the remainder of the apparatus. Fig. 5 is a fragmentary plan view of a record changer utilizing a modified feed construction. Fig. 6 is a sectional view on broken line 6—6 of Fig. 5. Fig. 7 is a top plan view of the feeding portion of the changer shown in Figs. 5 and 6. Fig. 8 is an elevation of the feeding member shown in Fig. 7 removed from the remainder of the apparatus.

The changer comprises baseboard or motorboard 10 preferably of sheet steel or the like upon which the entire apparatus is mounted. Baseboard 10 may have any desired shape and, as shown here, is generally rectangular having circular well 11 in the central portion thereof. Centrally disposed in well 11 is spindle 12 having straight portion 13, the upper end of which has tapered bent portion 14 terminating in offset tip portion 15. Spindle 12 is stationary and is supported in sleeve 17 rigidly attached to well 11. Sleeve 17 has set screw 18 adapted to bear against flat face 19 of portion 13 on the spindle. The spindle is mounted so that bent portion 14 extends toward corner 20 of the baseboard.

Turntable 25 has central portion 26 and depending flanged rim 27 adapted to fit within well 11. Turntable 25 is driven by a motor and suitable means not shown. The motor may be controlled by pushbutton 34.

Tone arm 36 of any desired construction is provided. This tone arm is pivotally mounted

2

at 37 for vertical movement. Suitable means not shown may be provided for operating the tone arm in order to lift the same and to rotate the same during a record changer cycle for proper changer operation. As an example, the means disclosed and claimed in the application referred to previously may be used. Other arm-elevating and driving means may also be used as desired.

Disposed in the corner of the motorboard adjacent the tone arm pivot is a rotary cam assembly for feeding records. Thus motorboard 10 carries journal portion 60 within which is disposed pin 61 for rotary movement. The journal axis and pin are preferably inclined from the vertical toward the spindle axis, this being the axis of straight portions 13. The angle of inclination may vary and, in practice, may be of the order of about 10°. Disposed above journal portion 60 is auxiliary journal portion 62. Portion 62 has tongue 63 cooperating with a slot in journal portion 60 whereby auxiliary portion 62 may be located in either one of two positions, these positions being 180° apart. Pin 61 extends up into auxiliary journal 62 and carries gear 65 at the upper end of the pin. Between gear 65 and a shoulder in journal portion 62, spring 66 is disposed around the pin to bias auxiliary portion 62 down against journal portion 60. Portion 62 carries pivot pin 67 parallel to but offset from pin 61. Pivot pin 67 has pinion 68 disposed on the same and meshing with gear 65. Pinion 68 and gear 65 have a one to one gear ratio. Thus, when portion 62 is turned 180° with respect to part 60 it will be found that pinion 68 is turned 360° with respect to its own axis. Figures 1 and 2 show the two possible positions for this part for two record sizes, the dotted line position being for a 10" record.

Pinion 68 is rigidly attached to member 70, functioning as a combined record supporting and feeding member. Member 70 has central portion 71 and stepped ledges 72 and 73. Ledges 72 and 73 have coincident leading ledges 74 and 75. The step between ledge 72 and ledge 73 is generally perpendicular to the plane of these ledges and forms two arcuate surfaces 76 and 77 joined by intermediate cam surface 78. The height of these surfaces is no greater than the thickness of a single record.

It will be noted that surface 77 has a greater radius than surface 76. The width of ledge 73 should be greater to support the edge portion of a record while the angular extent of ledge 73 should be such that the trailing edge will clear

55

a record when member 70 has been moved to its dotted line position shown in Fig. 3. The leading portion of ledge 72 bounded by surface 76 should be narrow enough so that the edge of a record may bear against the surface. The trailing portion of ledge 72 bounded by surface 77 should be wide enough so that this trailing portion may slide under the record above the bottom one and support the same. The angular extent of ledge 72 should be such that the trailing portion will still be under a record when member 70 is in its dotted line position as shown in Fig. 3.

The stepped ledges are generally flat and lie in planes substantially perpendicular to the axis of pin 61. However, the trailing portion of the lower ledge has surface 80 dropping down toward the turntable. This is shown in Fig. 4. Trailing portion 80 of the lower ledge may be substantially flat and somewhat lower than the plane of the ledge proper.

Member 70 carries record retaining block 82, having active face 83 for bearing against the edge of a stack of records in position during the feeding action. In the normal position of member 70, record retaining part 82 has active face 83 opposed to spindle 12. Face 83 extends down and merges with surface 76 at any desired part thereof, the height of face 83 being equal to the thickness of a stack of at least three or four records. Additional records above the bottom three or four of a stack need not engage face 83.

Record feeding action is obtained by rocking member 70 clockwise as seen in Figures 1 and 3 so that the edge of a bottom record which normally engages surface 76 is engaged by cam surface 78. As shown in Fig. 3, the rocking range is about 90°, although this may be varied. This causes the bottom record of a stack to be moved in its own plane toward spindle 12. Further turning movement of member 70 brings surface 77 into engagement with the edge of the bottom record to maintain the record in feeding position. Sloping surface 80 of lower ledge 73 aids in this feeding action. Records above the bottom are supported by the outer part of ledge 72. When member 70 reaches the dotted line position shown in Fig. 3, the bottom record will have dropped. Reverse movement of member 70 in counter-clockwise direction as seen in Figures 1 and 3 returns member 70 to its normal full line position as shown.

The means for accomplishing the above oscillation may be as disclosed and claimed in the application previously referred to. Other means for rocking member 70 over its prescribed range at proper times during a changer cycle are well known in the art and may be utilized. It is understood that the means engaging a diametrically opposed part of the bottom record to be described, aids in the record feeding action.

Disposed in corner 20 of the motor board is a means for supporting the edge portion of the bottom record only of a stack at a point on the record diametrically opposed to the region of support offered by record supporting member 70. This means comprises journal 90 rigidly supported on motorboard 10 in any suitable fashion. This journal has top face 91 having slot 92 therein. Resting on top face 91 is record supporting member generally designated by numeral 93 and having base portion 94. Base portion 94 has locks engaging slots 92 for rotatably locking the record supporting member in position. Record supporting member 93 has rigidly

attached thereto pin 95 extending downwardly as shown in Fig. 2 through journal 90 and below the motorboard. Pin 95 carries washer 96 at the bottom end thereof and has spring 97 around the pin between washer 96 and the bottom of the motorboard. It will be evident that spring 97 biases record retaining member 93 downwardly against journal 90.

Member 93 may be pulled vertically up against the bias due to spring 97 and be locked in one of two positions 180° apart. In either of these positions, one being for 10" records and the other for 12" records, record supporting member 93 extends generally radially of the turntable.

Record-supporting member 93 has elongated body 100 supporting two spaced upstanding posts 101 and 102. These posts in either of the positions of member 93 are along a radius from the center of the turntable.

Posts 101 and 102 are generally similar. Thus each of the posts, shown in greater detail in Figure 9, has a pair of jaws 103 and 104 defining generally horizontal slot 105 having a width somewhat greater than the width of a single record but less than the width of two records. Jaw 104 preferably has the slot side tapered at the bottom. Disposed within slot 105 is plunger 108 urged forward toward the slot opening by spring 109 carried by block 110 on the post.

Post 102 generally has the same construction as post 101 and as shown in Figure 2 is adapted to be in one of two positions for accommodating either 10" or 12" records. In one position, the 12" record position shown in full line in Figures 1 and 2, post 101 cooperates with a record while post 102 is inoperative. In the dotted line position obtained by raising member 93 and rotating the same 180° and then dropping the same into locking position, post 102 is operative to support a record while post 101 is inoperative. It is understood that the adjustments of record feeding member 70 and record supporting member 93 must be made so that both operate on the same size record together. Suitable means may be provided for moving these two members simultaneously.

In all record changers, means must be provided for controlling the drop of the tone arm so that the needle is started at the edge of a record. Thus the tone arm drop for a 10" record will be different than for a 12" record. In order to provide for this, lever 115 coupled to washer 96 may extend to suitable means not shown for controlling the dropping point of the tone arm. It will be evident that the position of lever 115 will be governed by the position of record supporting member 93. Means cooperating with lever 115 for controlling the position of the tone arm drop are described in the application previously identified. Other means well known in the art may be used.

The changer mechanism so far described is adapted for use with means for rocking or oscillating record feeding member 70. It is possible, however, to provide a record feeding member operating generally along the same lines as shown in Figures 1 to 4 inclusive with the exception that the record feeding member is turned in one direction only, it being understood however that the movement of the record feeding member is intermittent and occurs only when a record changing cycle is to occur. Such a modification is illustrated in Figures 5-8 inclusive.

Referring now to Figures 5-8 inclusive the mechanism is generally similar to the mechanism

previously described with the following exception. Pin 61' is adapted to be turned in one direction only for 360° for each changer cycle. Pin 61' carries pinion 65' which meshes with pinion 68' as in Figure 2. The journal and mounting and adjustment for 10" and 12" records is the same in both Figures 2 and 6. Record feeding member 70' however differs from member 70 in Figure 2. Member 70' has central portion 71' surrounded by stepped ledges 72' and 73'. Ledge 10 73' has sloping portion 80' terminating in record supporting lip 80a. Ledges 72' and 73' are connected by sloping portion 80b so that in effect a continuous inclined circular record support is provided beginning with part 80a along 73' and 15 80b to 72'. Ledge portion 72' terminates in portion 74'.

The stepped ledges generally lie in planes substantially perpendicular to the axis of pin 61' as in Figure 2 it being understood however, that sloping portions 80' and 80b are excepted. The inner portion of these ledges terminate in generally cylindrical surface 83' which may have any desired height and preferably extends upwardly for a distance corresponding to the thickness of several records. This portion of the changer in general corresponds to face 83 in Figures 1-4 inclusive. Head portion 83a may be provided for the sake of appearance.

The portion of the mechanism diametrically opposite member 70' is shown as being the same as in Figures 1-4 inclusive. It is understood that the corresponding record support disclosed in the application previously identified may be used in the two modifications disclosed herein.

What is claimed is:

1. In an automatic record changer of the drop type having a turntable with a stationary spindle having an offset portion for supporting a stack of records with the bottom record movable edge-wise into dropping position, the combination of a record feeding member, means for mounting said record feeding member for movement about a generally vertical axis, said record feeding member being disposed to support a record stack at one edge portion and being adapted to move the bottom record into dropping position, said member comprising a pair of generally concentric stepped arcuate ledges, the bottom ledge being nearer the spindle, said two ledges being separated by a generally vertical arcuate wall having a height no more than the thickness of one record, said top ledge tapering in width to provide a cam surface on said wall for moving the edge of the bottom record toward the spindle upon rotation of said record feeding member, said bottom ledge having two portions of different thicknesses connected by a sloping ledge portion, the thinner ledge portion being in the trailing part thereof, said sloping ledge portion being angularly displaced from the cam wall portion so that upon rotary movement of said member the record above the bottom may drop to the lower ledge when the bottom record has been dropped upon the turntable, said record feeding member normally being in a position where the lower ledge supports the bottom record of a stack and when said changer begins to cycle and turns said member, said cam wall engages a record edge and, upon further movement of said member, said sloping ledge portion comes in under the succeeding bottom record after which said member is

moved to its normal position and means for supporting only the edge of the bottom record at a point diametrically opposed to the point of support of said record feeding member.

2. The structure according to claim 1 wherein means are provided for oscillating said record feeding member, the ledges having an angular extent of substantially less than 360°.

3. The structure according to claim 1 wherein members are provided for moving said record feeding member in one direction only and wherein in said stepped and sloping ledges form a continuous record supporting surface around the member.

4. The structure according to claim 1 wherein said record feeding member has a portion above the top ledge provided with a generally vertical face for engaging the edges of records above the bottom of the stack.

5. The structure according to claim 1 wherein the ledges have an angular extent of substantially less than 360° and wherein said member has a portion rising above the ledges to provide a generally vertical face for engaging the edges of the records above the bottom.

6. The structure according to claim 1 wherein said stepped and sloping ledges form a continuous record supporting surface around the member and wherein said member has a portion providing an annular vertical face for engaging the edge of records above the bottom record.

7. The structure according to claim 1 wherein said last named means comprises a vertical post having a generally horizontal slot.

8. The structure according to claim 1 wherein said means for moving said member includes a pair of meshing pinions having a one to one ratio, means for mounting said record feeding member upon one pinion, means for mounting said one pinion so that it may be moved as a planetary gear around the other pinion as a sun gear, said pinions having their axes generally vertical and wherein means are provided for locking said record feeding member in one of two positions 360° apart with reference to the axis of said one pinion whereby said member may be moved toward or away from the spindle for accommodating different size records.

9. The structure according to claim 8 wherein said last named means comprises a post carrying two slotted members, the slots being generally in a horizontal plane, said slotted members normally being in line with the spindle and means for locking said slotted members in either of two positions 180° apart to bring one of the slotted members into cooperating position with a record, said two slotted members being adapted to support 10" or 12" records.
